UNITED STATES PATENT OFFICE.

PAUL F. COX, OF CHICAGO, ILLINOIS.

ADDRESSING MECHANISM (STRIP).

Application filed October 16, 1919. Serial No. 331,151.

To all whom it may concern:

Be it known that I, PAUL F. Cox, a citizen of the United States, residing at Chicago, in the county of Cook and State of Illinois, have invented certain new and useful Improvements in Addressing Mechanism (Strip); and I hereby declare that the following is a full, clear, and exact description thereof, reference being had to the accompanying drawings, which form part of this specification.

This invention is a novel mechanism for addressing articles, such as envelopes, packages, newspapers, and the like, by printing thereon or applying to each of such articles the address of the person for whom it is intended.

The invention is adapted for use in connection with printing presses and other mechanisms handling articles so that when the articles are delivered they are also addressed and ready for mailing.

The invention provides an addressing mechanism which is particularly adapted for attachment to a newspaper printing press and adjacent the folder former so as to print different addresses upon successive impressions, or newspapers, as they pass down the former, and preferably before the web is severed and before the printed sheets pass into the folding rolls.

When the novel mechanism is attached to an ordinary printing press or newspaper press the web handling mechanism of the press serves as the feeding and delivery mechanism for the addressing attachment, and the power mechanism of the press serves as the actuating means for the addressing mechanism. The addressing mechanism is compact and economical, and can be readily adapted for and applied to any of the standard makes of web printing machines.

In the present invention the addresses are previously printed on a long narrow strip of paper and the mechanism is adapted to detach the addresses successively from this strip of paper and apply them to the article, paper or web passing through or by the addressing mechanism. When the addressing mechanism is applied to a newspaper web

press the addresses are applied to the successive newspapers, preferably as they pass down the former, the former being used as the platen of the address applying devices.

I do not consider the invention restricted to the specific construction of the addressing mechanism shown, but will explain the same with reference to the accompanying drawings which illustrate one practical embodiment of the invention and will enable others skilled in the art to readily adapt and use the same. The essentials of the invention and novel combinations of parts and novel features of construction for which protection is desired are set forth in the claims.

In said drawings, Fig. 1 is a longitudinal section of the addressing mechanism attached to the frame of a printing press, in operative relation to the folder former.

Fig. 2 is a top plan view thereof.

Fig. 3 is a detail view of the strip advancing mechanism.

The operative parts of the addressing mechanism are mounted in a suitable frame. The particular form of this frame is not material provided it affords proper support and bearing for the operative parts of the addressing mechanism.

The apparatus is especially adapted for use in connection with printing presses and to address the newspapers or other printed articles as they are printed on the machine, and preferably the frame is so constructed that it can be readily attached to the frame of a printing press in such position that the addresses are applied to the web or sheets descending the folder former of such machine.

In the drawings I have diagrammatically illustrated part of a printing press to which the invention is applied; but the press may be a rotary, flat bed, or other type of press.

In the drawings F designates the folder former of a printing press, R the usual roller at the top of the former mounted on a shaft S, which is rotated as indicated by the arrow so as to assist the web of paper W to and over the former. The shaft S is driven by the usual gearing (not shown) and above the shaft S is a tie rod T, which

usually carries the spring pressed control rollers (not shown) which hold the web W in contact with the roller at the top of the former. Below the shaft S is a bar or rod 5 B which supports the upper end of the former F. All of these parts are of ordinary construction and arrangement and will be readily understood.

In the particular embodiment of the invention illustrated the addressing attachment frame 1 is connected with and supported by the rods T and B, and said frame 1 is shown as provided with an arm 1^a, which is secured by a split collar 1^b and bolts 1^c to the rod T, and the base member 1^d is supported upon the tie bar B and detachably attached thereto by clamping bolt 1^e, as indicated in the drawing.

In the embodiment of the invention illustrated in the drawings the addresses are successively printed upon a narrow strip or web of paper A, which may be wound in a roll upon a spool 8, the shaft 8^a of which may be detachably supported in a bracket 25 1^m on the frame 1. The strip of addresses is preferably perforated or weakened between successive addresses so that the successive addresses may be readily detached from the strip like stamps.

30 The address strip A is led from the roll 8 to and over a feeding roller 2, rotatably mounted on a stud 1ⁿ attached to the frame 1. This roller 2 is preferably provided with pins 2^a adapted to engage a series of longitudinal perforations in the strip A to ensure the accurate feed of the latter. The roller 2 may be operated so as to feed the strip forward preferably step by step by any suitable means. As shown it is provided with 35 a ratchet 2^b on one end engaged by a pawl 2^c, pivotally mounted on a gear 2^d loosely mounted on the stud 1ⁿ adjacent the ratchet; gear 2^d is engaged by a rack bar 2^e held in mesh with the pinion by a guide 2^f also 40 pivotally mounted on the stud 1ⁿ beside the gear 2^d; and the said rack bar is pivotally connected to a crank pin or stud 4^t on the hub of the rotary presser member, or other suitable part, so that the rack bar is oscillated once for each rotation of said member, and causes gear 2^d to oscillate and thus impart the desired extent of rotary movement 45 to roller 2 at and in the proper times.

The strip may be guided and lightly held 50 in contact with the surface of the feeding roller by any suitable means; a guard plate 2^g is shown in the drawings; and, if desired, a presser roller 2^h may be arranged beside the feed roller 2^a and coact therewith 55 to feed the strip. From the roller 2^h the strip is directed downwardly past a guide plate 3 which is secured to the frame 1, and in the example shown lies close to the face of the former F.

60 Pivotaly mounted on the frame 1, oppo-

site the lower part of the guide 3, is a guide plate 3^a, which is shown as provided with a projection 3^b adapted to be engaged by a cam member 4^e on the presser member 4, to cause guide 3^a to clamp the strip just before and while the presser pad is applying the leading address-stamp to the paper. The guide plate 3^a may be normally slightly separated from the guide 3 by any suitable means, such as a spring 3^c.

75

The mechanism shown is adapted to feed the address strip in such time and manner that one of the address stamps, or sections of the strip A, will be projected below the edge of the guide 3 and closely adjacent the former in position to be applied to the paper or web W descending the former F, and preferably in the margin between impressions thereon, by suitable pressing means.

As shown the pressing member 4 is 85 mounted on an arm 4^b attached to a shaft 4^c suitably journaled in the frame 1, and the shaft 4^c should be rotated at such speed that the presser member 4 will apply an address stamp to the web for each rotation of said 90 shaft 4^c.

The presser member 4 preferably has a yielding pad or face 4^a, of any suitable material, to contact the address strip. The arm 4^b is provided with a cam extension 4^e 95 that is adapted to engage the projection 3^b on the guide plate 3^a, just before the pad 4^a engages an address stamp, and cause the guide 3^a to clamp or bind the address strip against the clamp 3 when one address section or stamp depends below the guide 3 in position to be engaged by the pad 4^a, and such projecting address stamp will be detached from the strip by the action of the pad 4^a and applied to the paper as the latter 100 travels down the former.

100

The shaft 4^c may be rotated by any suitable means. As shown it is provided with a gear 4^f meshing with an intermediate gear 4^g, which may be journaled on a stud 1^o 110 on frame 1, and meshes with a gear 5^a on a shaft 5 journaled in the frame 1. The gear 5^a may be driven by a train of gears 5^b, 5^c journaled on studs in the frame 1, and the gear 5^e meshes with a gear 5^d on the shaft S, 115 so that the operative parts of the addressing mechanism are actuated from the shaft S, which is operated from the power driven part of the machine.

105

The address strip A may be coated with 120 an adhesive on the reverse side and in that case suitable means should be provided for moistening the adhesive side of the address stamp before it is applied to the web W. I preferably apply moisture to the spot of 125 paper to which the address stamp is to be applied, and then apply the address stamp to this dampened spot. For this purpose I provide a spot-dampening means of any suitable kind. In the construction shown this 130

- spot dampener comprises a pad 6 mounted on arm 6^b attached to the shaft 5. This spot dampener 6 may be a felt pad moistened in any suitable way. For convenience the arm 6^b 5 can be made hollow and contain water which can be introduced therein through an opening closed by a suitable stopple, indicated at 6^c, so that this container will hold enough water to keep the moistener damp for any 10 desired run of the machine. In some cases, if desired, the spotting pad could apply paste to the web instead of water—and in that case the address strip need not be coated with adhesive.
- 15 The spot dampener is so positioned and timed that it will apply water (or paste) to a spot on the paper web W large enough to receive the address stamp just prior to the address stamp being applied. Thus as the 20 web descends the former it is first spotted at the point S¹ and then stamped at the point S². The spotting pad travels in an orbit and at a speed coincident with the linear travel of the web over the former; and 25 the stamping pad 4^a is similarly moved.

Operation.

While I have described the addressing mechanism as applied to the former of a 30 web printing press it may be located at any convenient point in such press between the feeding and the folding devices; the parts being preferably so applied and driven that the spotting and stamping will be done without 35 interrupting the movement of the web.

In the example shown the gearing is so proportioned that the spot dampener 6 and the press stamp applying pad 4^a will each be rotated once for each article or impression 40 on the paper, or for each newspaper, when applied to a newspaper printing press; and the parts are so adjusted that the different addresses will be successively applied to the 45 articles preferably in the margins between successive impressions, or newspapers, so that each article as it passes the addressing mechanism, or each newspaper as it passes over the former, has the address of the individual for whom it is intended applied to 50 it before it reaches the folder rolls.

When the device is used as an attachment for printing presses the gear 4° can be split and bolted to the shaft S and the frame 1 attached to the tie rod T and bar B as described, to position the addressing mechanism beside the former. Impression rollers 55 7 and 7^a can be attached to the underside of the former in the proper position to respectively co-act with the spotter 6 and presser 4, if desired; the former being suitably slotted to accommodate these rollers.

When such an addressing attachment is applied to a printing press the papers can be delivered therefrom addressed to different 60 65 parties or destinations, ready for mailing;

and the necessity for subsequently addressing such papers, or passing such papers through an addressing machine is avoided; as well as the loss of time required for such operations; and the expense entailed in operating a separate addressing machine is eliminated. The addresses are preferably applied to the margin of the page of the newspaper which will be outermost when folded, and customarily the press is so 70 threaded that the outermost page is on the outside layer of paper passing over the former so that no rearrangement of the forms in the press would be ordinarily necessary in order to use the attachment there- 75 with. 80

By locating the addressing attachment at the former and printing the addresses upon the papers as they pass over the former the attachment is in the most convenient place for operation upon the paper; the addressing devices can be readily adjusted to correctly apply the addresses upon the margins whenever the papers are being properly delivered to the folding rolls; and 85 the addressing apparatus is not in the way when it is necessary to thread the press or folder, in making ready the press, or in case of rupture of the web. Other advantages 90 of the invention when used as an addressing 95 attachment for printing presses will be readily appreciated by those familiar with the art.

While I have described the invention as embodied in an attachment for web printing 100 presses and applied to such presses it will be obvious to those skilled in the art that the invention could be readily embodied in a separate machine for addressing letters, envelopes, packages, and the like. In such 105 case the frame would be properly modified, and means provided for rotating the shaft 4^e manually or by power, all of which will be readily understood and provided by those familiar with the art.

Having described my invention what I claim is:

1. In combination with means for printing and folding papers including a folder former; of means for detaching different address stamps from a strip and applying such stamps to different impressions on the paper as it descends the former.

2. In combination with means for printing and folding papers including a folder 120 former; of means for spotting the web and means for applying address stamps to the spotted portions of the web of paper as it descends the former.

3. In combination with means for printing and folding papers including a former for folding the paper after printing; means for spotting successive impressions on the web while it is passing down the former; and means for thereafter applying the ad- 125 130

dressess of different subscribers on the spotted portions before they reach the folder rolls.

4. In combination with means for printing and folding papers including a folder former; of means for dampening the web in spots and means for applying address stamps to such spotted portions of the web of paper as it descends the former.

10 5. In combination with means for printing and folding papers including a former for folding the paper after printing; means for dampening spots on successive newspaper impressions on the web while it is passing over the former; and means for thereafter applying address stamps upon the spotted portions of the web before they reach the folder rolls.

20 6. In a printing press in combination with means for printing and folding papers in which the paper is printed and then passed over a folder former; means adjacent the former for applying a fluid to spots on successive papers; and means for thereafter applying addresses on the spotted portions of the paper as it descends the former.

30 7. In combination with means for printing and folding papers; means for applying a fluid to spots on the margins of successive impressions on the paper before it passes the folder former; means for feeding an address strip; and means for applying different addresses from such strip to the spots on the paper as it passes over the former.

35 8. In combination with means for printing and folding papers including a folder former; of means for applying a fluid to spots on the margins of successive newspaper impressions on the web of paper as it descends the former; means for feeding an address strip; and means for applying addresses from the strip to the spotted portions of the web while it is passing over the former.

45 9. In combination with means for printing and folding a newspaper web including a folder former; means at the former for applying water to spots on different newspaper impressions on the web; means for feeding an address strip toward the former; and means for applying addresses from such strip to the spots on successive newspaper impressions on the web as it passes down the former.

55 10. In combination with means for printing and folding papers in which the paper is printed and then passed over a folder former; means adjacent the former for applying water to spots on the successive newspaper impressions on the paper; and means for thereafter applying different address stamps to the spotted portions of the paper as it descends the former.

60 11. In combination with means for printing and folding papers; means for applying

water to spots on the margins of successive impressions on the paper before it reaches the folder; means for feeding an address strip; and means for applying different address stamps from the strip to the spots on the paper as it passes over the former.

70 12. In combination with means for printing and folding papers including a folder former; of means for applying water to spots on the margins of successive newspaper impressions; with means for detaching address stamps from an address strip and applying them to the spotted portions of the web while it is passing over the former.

75 13. In combination with means for printing and folding a newspaper web including a folder former; means at the former for applying water to spots on different newspaper impressions on the web as it passes down the former; means for feeding an address strip toward the former; means for detaching address stamps from such strip; and means for applying such stamps to the spots on successive newspaper impressions on the web as it passes down the former.

80 90 14. In combination with means for printing and folding papers including a former for folding the paper after printing; means for feeding an address strip adjacent the former; and means for applying an address from such strip to the successive papers as they descend the former.

85 95 15. In combination with means for printing and folding papers in which the paper is printed and then passed over a folder former; means adjacent the former for feeding an address strip; and means for applying different addresses from such strip to the successive newspaper impressions on the paper as it descends the former.

100 105 16. In combination with means for printing and folding papers including a folder former; of means for feeding an address strip beside the former in unison with the movement of successive newspaper impressions on the web of paper as it descends the former; and means for applying addresses from the strip to the impressions on the web while it is passing over the former.

110 115 17. In an addressing mechanism the combination of a feed roller; means for feeding an address strip; means for detaching successive stamps from said strip; means for clamping the strip adjacent the impression point; and means for applying the address stamps to the paper with means for applying moisture to only that portion of the paper to which the address stamp is to be applied.

120 125 18. In an addressing mechanism the combination of a feed roller; means for feeding an address strip; means for clamping the strip adjacent the impression point; and means for detaching and applying the address stamps to the paper; with means for

130

directing paper past the stamping point; and means for applying a liquid to the spot on the paper where the stamp is to be applied before the paper reaches the stamp applying point.

19. In an addressing apparatus the combination of a feed roller for a stamp strip; a guide directing the strip to the applying point; a member for clamping the strip; a rotatable member adapted to apply a stamp when detached from the strip; means on said member for causing the clamp to hold the strip just before the stamp is applied; and means connected with said stamp applying member for imparting a step by step movement to the strip feed devices.

20. In an addressing apparatus the combination of a feed roller for a stamp strip; a guide directing the strip to the applying point; a member for clamping the strip; a rotatable member adapted to apply a stamp when detached from the strip; means on said member for causing the clamp to hold the strip just before the stamp is applied; and means connected with said stamp applying member for imparting a step by step movement to the strip feed devices; with means for directing the paper past the stamping point; and means for applying stamp liquid to a spot on the paper where the stamp is to be applied before the paper reaches the stamp applying point.

21. In combination with means for printing and folding papers including a folder former; of an addressing mechanism, comprising a frame adjacent the folder former; a strip carrier mounted on said frame; a strip feeding roller mounted on said frame; a strip guide mounted on said frame; a strip clamp adjacent the guide; a rotatable presser member adapted to apply the stamp upon the paper descending the former; means on said member for causing the clamp to engage the strip when an address stamp is projected into applying position; and means actuated by said member for imparting a step by step motion to the feeding roller.

22. In combination with means for printing and folding papers including a folder former; an addressing mechanism comprising a frame adjacent the folder former; a strip feeding means mounted on said frame; a strip clamp adjacent the guide; a rotatable pressure member adapted to apply the stamps upon the paper descending the former; means for causing the clamp to engage the strip when an address stamp is projected into applying position; and means actuated by said member for imparting motion to the strip feeding means; with means for applying liquid to the spot on the paper where the stamp is to be applied before the paper reaches the stamp applying point.

23. In combination with means for printing and folding papers including a folder

former; of an addressing mechanism, comprising a frame adjacent the folder former; a strip carrier mounted on said frame; a strip feeding roller mounted on said frame; a strip guide mounted on said frame; a strip clamp adjacent the guide; a rotatable presser member adapted to apply the stamp upon the paper descending the former; means on said member for causing the clamp to engage the strip when an address stamp is projected into applying position; and means actuated by said member for imparting a step by step motion to the feeding roller; with means for applying water to the spot on the paper where the stamp is to be applied before the paper reaches the stamp applying point.

24. In an addressing mechanism the combination of a strip feed roller; means for intermittently operating said roller; means for detaching successive stamps from said strip; means for clamping the strip adjacent the impression point; and a presser member for detaching and applying the address stamps to the paper; with means for directing the paper past the stamping point; a rotary member adjacent the stamping point, and a spot moistener carried by said member for applying liquid to the spot on the paper where the stamp is to be applied before the paper reaches the stamp applying point.

25. In an addressing mechanism; a frame; a strip feeding means mounted on said frame; a strip clamp; a presser member adapted to detach the stamp and apply the same upon the paper; means for causing the clamp to engage the strip when an address stamp is projected into applying position; and means for imparting motion to the strip feeding means; with means for directing the paper past the stamping point; a rotary member adjacent the stamping point, and a spot moistener carried by said member for applying liquid to the spot on the paper where the stamp is to be applied before the paper reaches the stamp applying point.

26. In combination, an addressing mechanism comprising a frame; a strip feeding means mounted on said frame; a strip clamp adjacent the guide; a rotatable presser member adapted to detach the stamp and apply the stamp upon the paper; means for causing the clamp to engage the strip when an address stamp is projected into applying position; and means actuated by said member for imparting a motion to the strip feeding means; with means for directing the paper past the stamping point; a rotary member adjacent the stamping point; and a spot moistener carried by said member for applying liquid to the spot on the paper where the stamp is to be applied before the paper reaches the stamp applying point.

27. In combination; a frame; a strip feeding means mounted on said frame; a strip clamp presser member adapted to apply the stamps upon the paper; means for causing the clamp to engage the strip when an address stamp is projected into applying position; and means for imparting motion to the strip feeding means; with means for directing the paper past the stamping point, a ro-

tary member adjacent the stamping point, 14 and a spot moistener carried by said member for applying liquid to the spot on the paper where the stamp is to be applied before the paper reaches the stamp applying point.

In testimony that I claim the foregoing 15 as my own, I affix my signature.

PAUL F. COX.
